The ornamental design for a toddler coat with an integral blanket and pocket, as shown and described.

DESCRIPTION

FIG. 1 is a front perspective view of the toddler coat with an integral blanket and pocket showing the blanket extended; FIG. 2 is a front elevation view of the toddler coat with an integral blanket and pocket;

FIG. 3 is a top plan view of the toddler coat with an integral blanket and pocket;

FIG. 4 is a side elevation view of the toddler coat with a integral blanket and pocket, (the opposite view being identical thereto);

FIG. 5 is a rear elevation view of the toddler coat with an integral blanket and pocket showing the integral blanket extending from the pocket disposed on the back of the coat; and,

FIG. 6 is a bottom plan view of the toddler coat with an integral blanket and pocket.
